BY *Fred C. Fraenzel* ATT'Y.

UNITED STATES PATENT OFFICE.

WILLIAM H. GARTZ, OF BERNARDSVILLE, ASSIGNOR TO WILLIAM HILL AND FREDERICK GARTZ, OF NEWARK, AND LOUIS A. GARTZ, OF ELIZABETH, NEW JERSEY.

SASH-FRAME AND VENTILATING-SASH.

SPECIFICATION forming part of Letters Patent No. 536,692, dated April 2, 1895.

Application filed August 9, 1894. Serial No. 519,861. (No model.)

To all whom it may concern:

Be it known that I, WILLIAM H. GARTZ, a citizen of the United States, residing at Bernardsville, in the county of Somerset and State 5 of New Jersey, have invented certain new and useful Improvements in Sash-Frames and Ventilating-Sash; and I do hereby declare the following to be a full, clear, and exact description of the invention, such as will enable others skilled in the art to which it appertains to 10 make and use the same, reference being had to the accompanying drawings, and to letters of reference marked thereon, which form a part of this specification.

15 My present invention has reference to improvements in combined ventilators and screens to be used in connection with the window-frame and window sash; and the invention therefore consists in certain novel arrangements and combinations of parts, such as will be hereinafter more fully described and finally embodied in the clauses of the 20 claim.

The invention is illustrated in the accompanying sheets of drawings, in which—

25 Figures 1 and 2 are views of the window frame and sash, provided with the ventilating screen embodying the principles of my present invention. Fig. 3 is a vertical section 30 taken on line *y* in Fig. 1; and Fig. 4 is a vertical section taken on line *z*, in Fig. 2. Figs. 5 and 6 are a front view and a side view respectively of a spring-catch used in connection with the window-frame and sash.

35 Similar letters of reference are employed in each of the above described views to indicate like parts.

In said drawings, *A* represents a window-sash frame, in which are arranged to slide up 40 and down therein, the upper window sash *a* and the lower window sash *h'*. Secured in the upper portion of the window sash is a suitable screen *b*, arranged in such a manner, that the edge *a'* of the upper window sash *a* is in sliding contact with any part of the face of said screen, whereby said sash can be moved up 45 and down in front of said screen to close or lower the sash from the top, as will be clearly understood.

50 To limit the downward movement of the up-

per sash when lowered, and to prevent the edge *a'* of the frame from being brought below the screen *b*, I have arranged on one side of the sash-frame *a*, a spring catch *C*, of the construction illustrated more especially in 55 Figs. 5 and 6. Said catch consists essentially of a plate *c*, secured by means of suitable screws, or in any other well-known manner, to the face of the window sash. In a central opening in said plate *C* is a suitable push-button 60 or finger knob *c'* on a short arm *c* connected with a spring *c* arranged in a recess in the sash. The end *c* of said spring is in sliding contact with the portion *a'* of the window frame *A*, so that when the upper sash is lowered to the position illustrated in Figs. 3 and 65 4, said end *c* of the spring *c* will force itself into a notch or recess *a* in the portion *a'* of the window frame and the upper sash is thus retained in said lowered position, so that the 70 edge *a'* will be brought into contact with the lowest part of the screen *b*, as shown.

When it is desired to lower the sash as far as possible, as for instance when it is necessary to clean the window, a slight pressure on 75 the button *c'* will disengage the end *c* of the spring *c* from the notch in the window frame and the sash can be lowered or raised at will.

I provide the upper sash *a* with a cross-piece *a* forming with the portions *a'* and *a* 80 of the sash a frame for a screen *d*. The cross-piece *a* is slotted in the bottom and sliding in suitable ways in the side portions *a* of the sash, is a suitable sliding panel *e* provided with a pane of glass *e'*, which may be of any 85 desirable color. By means of a pull or finger-piece *e* said frame *e* and its glass can be lowered, stops *e* on said frame, which come in contact with the upper edge of the cross-piece *a*, preventing said sliding pane from being 90 pulled out of the frame formed by the several parts of the sash frame. Thus it will be seen that the sash *a* can be lowered to the distance illustrated in Fig. 1, permitting the pure air to pass into the room through the screen *b*, 95 but should it be desirable to have more air in the room, the sliding panel *e* can be lowered and the air also passes through the screen *d*.

Having thus described my invention, what I claim is—

1. In combination, with a window frame and the upper sash, a ventilating screen, as *b*, secured in the upper portion of said frame, a cross-piece *a*⁵ in said sash, a ventilating screen *d*, and a sliding panel *e*, substantially as and for the purposes set forth. 25
2. In combination, with a window frame and the upper sash; a ventilating screen, as *b*, secured in the upper portion of the sash frame, a cross-piece *a*⁵ in said sash, a ventilating screen *d*, and a sliding panel *e*, and means connected with said upper sash to regulate the downward movement thereof, substantially as and for the purposes set forth. 30
3. In combination, with a window frame and the upper sash, a ventilating screen, as *b*, secured in the upper portion of the sash frame, a cross-piece *a*⁵ in said sash, a ventilating screen *d*, and a sliding panel *e*, and means connected with upper sash to regulate the downward movement thereof, consisting essentially of a spring catch *c*³, having a finger 35

knob *c*', and the end *c*⁴ of said catch being adapted to engage with a notch in the window frame, substantially as and for the purposes set forth. 25

4. A window sash, as *a*, having a cross-piece *a*⁵, a ventilating screen *d* in said sash, and a sliding panel *e* adapted to slide in said cross-piece *a*⁵, substantially as and for the purposes set forth. 30

5. A window sash, as *a*, having a cross-piece *a*⁵, a ventilating screen *d*, in said sash, and a sliding panel *e* adapted to slide in said cross-piece *a*⁵, a pull *e*² on said frame *e*, and stops *e*³, all arranged, substantially as and for the purposes set forth. 35

In testimony that I claim the invention set forth above I have hereunto set my hand this 6th day of August, 1894.

WILLIAM H. GARTZ.
